UNITED STATES PATENT OFFICE.

HENRY WALCOTT, OF ROCHESTER, VERMONT.

COVER FOR SAP-BUCKETS.

SPECIFICATION forming part of Letters Patent No. 380,958, dated April 10, 1888.

Application filed December 28, 1887. Serial No. 259,214. (No model.)

To all whom it may concern:

Be it known that I, HENRY WALCOTT, a citizen of the United States, and a resident of Rochester, in the county of Windsor and State 5 of Vermont, have invented a certain new and Improved Cover for Sap-Buckets, of which the following is a specification.

My invention relates to a removable cover for a sap bucket or pail, adapted to be employed 10 while the bucket is in use and receiving sap from the tree; and the object of my invention is partly to provide a cover that will be self-retaining and will keep out twigs, leaves, rain, &c., and partly to provide means in connection 15 with said cover for keeping back the ice (which sometimes forms in the bucket) when emptying the sap from the buckets.

My invention will be hereinafter fully described, and its novel features carefully defined 2 in the claims.

In the drawings which serve to illustrate my invention, Figure 1 is a side elevation of an ordinary sheet-metal sap-bucket provided with my improved cover. This view also 25 shows in dotted lines the sap-spout and hook for supporting the bucket when it is in use. Fig. 2 is an end or front view of the same, taken at right angles to Fig. 1, and showing the device for retaining the ice in the bucket at the 30 rear. Fig. 3 is a section on line 3 3 in Fig. 2, showing the interior of the cover. Fig. 4 is a section on line 4 4 in Fig. 1 at right angles to Fig. 3, illustrating the manner in which the cover is secured to the bucket. Fig. 5 is a top 35 view or plan of the cover.

These views are all drawn to the same scale.

X represents an ordinary sap-bucket, which may be of sheet metal and of the size and form usually employed in the manufacture of maple-sugar. Such a bucket has a projecting 40 wired bead or flange, as x, around its upper edge.

A represents my improved cover as a whole.

In constructing my cover I take a sheet of 45 metal, preferably tin-plate, cut it to the proper shape, and then form an elevated central portion or roof-section, a, therein, the ends of which extend out to or a little beyond the rim of the bucket to form hoods a' a'. The lateral 50 portions b b of the cover may be substantially level, and these are joined to the roof-section a

by sides c c, usually inclined or sloped, as shown.

Around the margins of the portions b are formed drop-flanges d d, which are wired at 55 their edges in such a manner as to form inturned flanges, which, when the cover is in place on the bucket, spring in and take under the wired bead x on the margin thereof, and thus serve by the elasticity or spring-like character 60 of the parts to retain the cover firmly in place. The cover may, however, be removed by a little effort. I also strengthen and stiffen the 65 cover and add to its spring-like retaining qualities by wiring the edges of the projecting hoods a' a' and the ends of the sides c c, and these wires may be continuous all around the margin of the cover. I have shown the cover constructed of a single sheet of metal; but this is not essential.

The elevation of the cover at its middle is 70 intended in the main to allow room for the sap-spout y. (Indicated in dotted lines in Figs. 1 and 3.) The bucket may be suspended from the spout by a hook, z, also indicated in dotted lines. This hook engages a hole, x', in the 75 side of the bucket just below the wired bead x.

Sometimes ice forms in the sap in the buckets, and it is desirable under most circumstances that this should not be allowed to get 80 into the conveying spouts, funnels, or pipes, into which the buckets are emptied. To prevent this, I provide my cover with an ice-guard, e, in the nature of a grid, which I usually make of wire and hinge by a clip, f, to 85 the under side of one of the hoods a'. The hinging of the guard permits it to be turned up out of the way, as seen in dotted lines in Fig. 3, when it is not required to be used. In placing the cover on the bucket the hood to which 90 the guard is hinged should be turned so as to stand away from the tree.

While my cover is designed to be employed 95 most particularly on sheet-metal buckets which have a wired, flanged, or beaded rim for the cover to engage, a wooden or other receptacle may of course be used in connection with the cover, provided said receptacle has a retaining bead or device of a similar character to that shown, or capable of engaging the cover-flange. 100

The degree of elevation and the width of the central section of the cover may be varied to

suit the circumstances and the manner in which the bucket is suspended from the spout.

I prefer to connect the parts *a*, *b*, and *c* by rather abrupt bends or angles, as these tend to stiffen the cover; but I do not wish to limit myself to this particular feature of the construction.

My cover is light, stiff, and spring-like as respects its retaining qualities when in place, so and they may be packed closely for shipment, as the projecting parts of one will fit or "nest" quite snugly into the hollows of the other.

Having thus described my invention, I claim—

15 1. A cover for a sap-bucket, made from sheet metal and wired at its edges, said cover consisting of the elevated roof-section *a*, the upright

sides *c c*, and the lateral portions *b b*, provided with inturned retaining flanges *dd*, whereby the cover is retained in place by its own elasticity, 20 as set forth.

2. A cover, *A*, for a sap-bucket, having an elevated central roof-section, *a*, forming hoods *a' a'*, and provided with an ice-guard attached to the under side of one of said hoods, substantially as set forth. 25

In witness whereof I have hereunto signed my name in the presence of two subscribing witnesses.

HENRY WALCOTT.
